C. Cook,

Steam Cut-Off.

No 10,591.

Patented Mar. 7, 1854.

UNITED STATES PATENT OFFICE.

CALEB COOK, OF NASHVILLE, NEW HAMPSHIRE.

ARRANGEMENT OF VALVE-MOTIONS FOR LOCOMOTIVE-ENGINES.

Specification of Letters Patent No. 10,591, dated March 7, 1854.

To all whom it may concern:

Be it known that I, CALEB COOK, of Nashville, in the county of Hillsboro and State of New Hampshire, have invented a new 5 and useful Improvement in Mechanism for Working the Valves of Engines of Locomotive Steam-Carriages; and I do hereby declare that the same is fully described and represented in the following specification 10 and the accompanying drawings, letters, figures, and references thereof,

Of the said drawings Figure 1 represents a top view or sketch of my said invention. Fig. 2 is a longitudinal sectional view of the 15 same.

In the said drawings A represents the shaft of an eccentric B, such shaft being the crank shaft of the engine, the crank of which is seen at N.

20 C is the valve rod, which is applied to the valve A' of the steam chest of the cylinder, the seat plate and ports of which are exhibited at B'. This valve rod is formed with a hinge D' where it is hinged to a 25 connecting rod C', such connecting rod being jointed at its other end to a curved bar or lever D, that extends upward from a bell crank rocker shaft E, that carries within its bell crank and attached to the outer part 30 of the same, a slotted lever G, which is formed as seen in the drawings. The lever D has a slot a formed through it, which is made curved and with a radius, whose center is at the central part of the joint 35 between the rods C and C'. The pin h upon which the rod C' turns extends through the said slot and is made with a shoulder (as seen at h' in Fig. 3, which is a side view of the pin) to rest against one side of the lever 40 D. It also has a screw and a nut adapted to it by which with the shoulder it may be confined in the slot at any elevation above the rocker shaft, whereby when said rocker shaft is in motion a greater or less stroke or 45 extent of movement of the valve over the ports will be effected. In this way I can make a cut off of the main valve.

The slot of the lever G is formed of two recesses a b, which are equally distant from 50 the axis of the shaft E, and disposed on opposite sides of it. The pin c, of the connecting rod H of the eccentric strap or ring I, rests in the lower recess a, and consequently when these and the eccentric is rotated it will cause the valves of the steam 55 chest to be put in operation.

In order to suddenly reverse the motion of the engine we have only to lift the rod H into the recess b. This may be effected by means of a cord or chain attached to it 60 and made to pass over a pulley and be pulled by an attendant or the engine man. By raising and lowering the eccentric rod, the strap on the eccentric is moved so as to give what is termed the lap and the lead of the 65 valve, the crank of the eccentric shaft being supposed to stand at a right angle with a line extending from the center of the shaft to that point in the circumference of the eccentric which is at the greatest distance 70 from the center of the shaft.

By means of my improvement, the engine may be instantly reversed, no matter what 75 may be its speed, and without a possibility of a failure in so doing. Such improvements enables a locomotive steam carriage to be run with two eccentrics for its two cylinders, whereas generally speaking four or six set of eccentrics are employed.

My improvement not only simplifies but 80 cheapens the construction of a locomotive.

I do not claim for operating the valves an arrangement wherein a link is employed and has attached to it the valve rod and the eccentric rod, the center pin of the link 85 working in the eye of a horizontal arm attached to a rocker shaft; nor do I claim a modification of such wherein would be the same link with the eccentric rod and valve rod attached and having the center pin of 90 the link moving in vertical or curved guides attached to the rocker shaft as such modifications do not admit of the reversion of the engine without the removing both the link and the eccentric rod, whereas with my improvement such can be effected by moving 95 the eccentric rod only.

I therefore limit my claim to my particular arrangement or construction of the open lever G, as provided with two recesses 100 and connected to a rocker shaft and applied to and made to operate with respect to the eccentric and valve rods substantially as described.

In testimony whereof I have hereunto 105 set my signature this thirteenth day of December, 1853.

CALEB COOK.

Witnesses:

A. B. COOK,
ALLEN NELSON,
